UNITED STATES PATENT OFFICE.

AUGUST STEINER, OF HOMEWOOD, ILLINOIS.

CORN-HUSKER.

SPECIFICATION forming part of Letters Patent No. 436,386, dated September 16, 1890.
Application filed March 10, 1890. Serial No. 343,244. (No model.)

To all whom it may concern:

Be it known that I, AUGUST STEINER, a citizen of the United States, residing at Homewood, in the county of Cook and State of Illinois, have invented a new and useful Improvement 5 in Corn-Huskers, of which the following is a specification.

The main object of this invention is to provide a machine which is capable of traversing the fields of corn and stripping the ears from the stalks, and then husking or shucking the same in a thorough manner; but, if desired, the machine may be used as a stationary one and the husking effectively produced.

15 The invention consists in the construction and combinations hereinafter described, and then more particularly pointed out in the claims.

Like letters refer to the same parts in the several figures of the drawings, in which—

Figure 1 is a plan view of my machine, arranged with two pairs of husking-rolls at right angles to each other. Fig. 2 is a longitudinal vertical section of the same. Fig. 3 is a vertical cross-section of my machine with the conveyer arranged so as to be immediately over the line between the pairs of rolls and showing the ears of corn immediately under such conveyer. Fig. 4 is a view in detail of two pairs of husking-rolls arranged in operative relation. Fig. 5 is a detail view showing the relation of the conveyer and divider to the rolls. Fig. 6 is a front end view of the conical guiders in position for operation, and 30 of a portion of the driving mechanism. Figs. 7 and 8 are detail views showing the manner of hinging the front portions of the conical guiders, and Fig. 9 is a detail perspective of the bow-spring and its connection to the two frames.

A is the main frame of the machine, and it is of such suitable material and construction as to best adapt it for the purpose intended.

Suitably journaled in the main frame is the 45 main or power shaft B. This power-shaft derives its motion from a pair of traction-wheels, as shown in the drawings, or in case the machine is stationary, from any suitable motor—hand, steam, electric, &c.

50 Ordinarily the ears of corn are shucked while upon the stalk, and one office of the

present invention is to detach the ear from the stalk as well as husk or shuck it. Accordingly a pair of rolls C C', called "snapping-rolls," are mounted in the frame, as will 55 hereinafter be described, and serve to detach or sever the ear from such stalk. In advance of the snapping-rolls are arranged suitable devices for feeding and guiding the stalks and the ears to the snapping-rolls. These devices, which I term "guiders," may be of various constructions; but I prefer to employ two conical and hollow pieces D D', which inclose chains or belts provided with spikes, which latter move along and extend through 60 longitudinal slots cut in the inner sides of the conical guiders. The spiked belts are lettered E E', and are mounted upon sprockets 65 suitably geared to and driven from the main or power shaft. The space between the guiders and between the spiked belts gradually 70 narrows as the snapping-rolls are approached, so that the corn may be strongly held and advanced as it is being delivered to such rolls. Just at this point of delivery it is well to 75 place curved guards or shields a a, behind which the spikes may turn, and thus prevent the corn from following the spikes on the belts. The forward portions of the conical guiders may be hinged to the rear portions, 80 as clearly shown in Figs. 7 and 8 of the drawings, so that such forward portions may be depressed to catch such stalks of corn as may not be standing upright. If the guiders were angular in cross-section there would be danger 85 of the stalks breaking while being drawn over such angles, and of the ears of corn falling upon the ground before being caught by the snapping and husking mechanism, and to avoid this danger I prefer to curve the ex- 90 posed portion of such guiders.

The snapping-rolls C C' are set a slight distance apart, with their rear ends journaled in a cross-bar of the main frame, but with their front ends journaled, respectively, in the main frame, and in a supplemental frame F, which latter will hereinafter be more particularly described. These rolls are formed with long spiral corrugations, so made that the corrugations of one roll mesh with those of the companion roll, and that the rolls have, respectively, right 100 and left corrugations. Such rolls are also

provided with spiral ribs O O, also arranged, respectively, to wind in a right and left direction, and of a different pitch from and longer pitch than the corrugations. The meshing 5 of the long right and left corrugations causes the rolls to grip or bite the stalks more firmly and thus force them along and through the rolls and snap off the ears, and at the same time rapidly convey the latter along without 10 assistance from the conveying devices. The corrugations of the rolls are rounded, so that they will not cut the stalks, for if they did the operation of the machine would be impeded by pieces of stalk, &c., but my round 15 corrugations merely forcibly snap the ears from the stems, allowing the stalks to pass through without breaking. If the corrugations fail to snap the ears from the stems of the stalk they will at least feed them forward 20 rapidly, and the spiral ribs will by a shearing action certainly effect the snapping. The long spiral of the ribs will cause a successive action, and will thereby prevent the choking so commonly resulting from the action of 25 straight ribs.

A bow-spring G, preferably made of steel, is fastened at one end to the front cross-bar of the main frame, and at its other end is detachably secured to and supports the supplemental frame F, and to the latter is attached 30 the conical guider D' and its spike-belt E', the bearings of the front journal of the roll C', and for the similar ends of the pair of husking-rolls H H'. Even if the rear journal 35 is rigidly supported and the rear end of the supplemental frame is similarly supported, yet the fact that the front ends of both are supported by the spring will enable such ends to have a certain lateral play because of the 40 elasticity inherent in such parts and the leverage afforded by their length; but, if desired, the said rear ends may be mounted so as to have a small play. Owing to the action 45 of my rolls the thick butts of stalks which enter between them will be quickly drawn downward, so that within a short distance of the forward ends only the thin tops of the 50 corn-stalks will be between them, and it therefore follows that a slight yielding at the front ends is all that is required. By this 55 construction the snapping rolls have an elastic relation, so that they may separate for extraordinary sized corn or to prevent a breakage of the parts when a stick, stone, or other obstruction is drawn between such rolls. The spring likewise permits the supplemental frame and the other parts mounted 60 therein to give or yield should such frame or parts meet with an obstruction or be placed under an uncommon strain, and at the same time the spring affords a convenient detachable support, whereby any of the parts secured to or mounted in the supplemental frame may be detached and replaced. 65 After the ear has been severed from the stalk it falls upon or is conveyed to the husking rolls.

In Fig. 1 of the drawings, I have shown a pair of husking-rolls H H', immediately adjacent and parallel to the snapping-rolls, and 70 another pair of similar rolls located at the rear of the machine and at right angles to said snapping-rolls. Such an arrangement is preferable when the shucks are unusually hard to remove from the corn, and in locations 75 where the crop of corn is very heavy it has been found advantageous to duplicate the pairs of rolls in lateral arrangement, as is shown most clearly in Figs. 4 and 5 of the drawings. It has been found, however, that 80 generally but one pair of husking-rolls need be employed, and in such event I prefer to arrange them at the rear of the machine and to have the ears of corn which fall from the snapping-rolls drop upon a platform and be 85 fed by a suitable conveyer to the husking-rolls. One husking-roll of each pair should have a raised rib with a serrated inner edge wound spirally around it, while the other roll 90 of the pair may have spirally-arranged rows 95 of pins project from its surface.

A chain belt I, provided with vertical paddles, is arranged over the husking-rolls and serves to convey the corn along and at the same time hold the ears down to the gripping 95 and husking action of such rolls. The husking-rolls are caused to revolve toward each other and the ear is held down upon them, and thus the pins and serrations will be constantly fastening themselves into the shuck 100 and tending to carry such shuck with them in their rotation; but as the ear cannot follow the shuck because the space between the husking-rolls is too small, it results that the shuck is stripped from the ear. Sometimes when the ear is delivered to the husking-rolls it falls upon its end and rests in an inclined position against one of the paddles 105 of the chain belt. Such a position would result in shelling the end of the ear without stripping the shuck from the same. To prevent this result I employ an inclined board L, having pins upon its under side and pivoted in the frame above the front ends of a pair of husking-rolls, with its lower end resting loosely thereon. The pins of this board 110 catch any ear of corn resting upon its end and hold it until the chain belt has carried the supporting-paddle from under the ear, and the latter is thus caused to be deposited 115 properly in the next compartment of such chain belt.

In the event of two parallel pairs of husking-rolls being employed it frequently occurs that an ear of corn will drop between such 125 pairs instead of between the rolls of one pair; and to remedy any evil which might result from such position a divider M is placed in advance of the husking-rolls on the line between the pairs, so that the ear must partially 130 rest upon such divider and will be swept therefrom and onto one or other of the pairs by the paddles of the chain belt.

A convenient form and arrangement of di-

vider is shown in Figs. 3 and 5 of the drawings, in which it is illustrated as consisting of a metal bar with a wedge-shaped face.

The snapping-rolls, the husking-rolls, the conveyor, and other revolving or traveling parts all derive their motion from the main or power shaft, being connected therewith by an arrangement of gearing like that shown, or by any other convenient arrangement.

10 Various modifications of the several features of my invention will readily suggest themselves to those skilled in the art, and I therefore do not desire to be confined to the precise construction shown and described.

15 What I claim, and desire to secure by Letters Patent, is—

1. In a corn-husker, a pair of rolls having long rounded spirally-corrugated surfaces, respectively, right and left in the different rolls 20 and adapted to mesh one with the other, substantially as and for the purpose set forth.

2. In a corn-husker, a pair of rolls having long right and left corrugations, respectively, the one adapted to mesh with the other, and 25 long spiral ribs projecting therefrom which are of different pitch from the spiral corrugations, substantially as and for the purpose set forth.

3. In a corn-husker, one or more pairs of 30 husking-rolls, each pair comprising a roll provided with long spiral metal ribs with serrated inner edges, and a roll having long spiral rows of pins which project within the plane of the outer surface of the spiral ribs, substantially as and for the purpose set forth.

4. In a corn-husker, the combination of a 35 pair of husking-rolls, a chain conveyor provided at suitable intervals of space with transverse paddles and arranged over said rolls, 40 with a pivotal plate or board having teeth or pins upon its under surface and located near

and above the forward ends of said rolls, whereby ears of corn which fall upon their ends into the conveyor are forced into a horizontal position before they reach the husking 45 mechanism, substantially as shown and described.

5. In a corn-husker, the combination of two or more pairs of husking-rolls and a chain conveyor provided with transverse paddles 50 arranged thereover, with a longitudinal di- vider between the pairs of rolls and in advance of the same, whereby ears of corn falling over two rolls belonging to different pairs will be swept by the paddles from the transverse po- 55 sition to a proper position with respect to one or other of the pairs, substantially as shown and described.

6. In a corn-husker, the combination of a main frame and a supplemental frame with a 60 bow-spring secured by one arm to the main frame and having the supplemental frame secured to its other arm, whereby an elastic connection between the frames is obtained and the supplemental frame is supported by such 65 spring, substantially as shown and described.

7. In a corn-husker, the combination of a main frame carrying one of the snapping or severing rolls and one of the projecting shoes or guiders and its spiked feeding-belt, with a 70 supplemental frame carrying the outer end of the other snapping-roll and the other projecting shoe or guider with its spiked feeding- belt, and a bow-spring having one of its arms secured to the main frame and serving to 75 support the supplemental frame and attachments by its other arm, substantially as and for the purpose set forth.

AUGUST STEINER.
